UNITED STATES PATENT OFFICE.

PHILIP PEZZELLA, OF BROOKLYN, NEW YORK.

DESIGN FOR A BEDSPREAD.

Application filed September 28, 1928. Serial No. 28,312. Term of patent 3½ years.

To all whom it may concern:

Be it known, that I, PHILIP PEZZELLA, a citizen of United States, residing at Brooklyn, in the county of Kings and State of New York, have invented a new, original, and ornamental Design for a Bedspread, of which the following is a specification, reference being had to the accompanying drawing, forming part thereof.

In the drawing the figure is a plan view of a bed-spread constituting the new design.

I claim:—

The ornamental design for a bed-spread, as shown.

PHILIP PEZZELLA.
